No. 36,536.

Patented September 8, 1903.

UNITED STATES PATENT OFFICE.

EUSTACE CREES AND CHARLES S. COURT, OF PROVIDENCE, RHODE ISLAND,
ASSIGNORS TO THE WATSON AND NEWELL COMPANY, A CORPORATION
OF RHODE ISLAND.

DESIGN FOR A HANDLE FOR SPOONS, FORKS, OR SIMILAR ARTICLES.

SPECIFICATION forming part of Design No. 36,536, dated September 8, 1903.

Application filed August 14, 1903. Serial No. 169,539. Term of patent 7 years.

To all whom it may concern:

Be it known that we, EUSTACE CREES and CHARLES S. COURT, citizens of the United States, residing in the city of Providence, in the county of Providence and State of Rhode Island, have invented a new, original, and ornamental Design for the Handle of a Spoon, Fork, or Similar Article, which is illustrated in the accompanying drawing, forming part of this specification.

The design is executed in relief.

What we claim is—

The ornamental design for the handle of a spoon, fork or similar article as shown.

In testimony whereof we have signed our names in the presence of two witnesses.

EUSTACE CREES.
CHARLES S. COURT.
